(57) **CLAIM**

The ornamental design for an occlusal dental mirror, as shown.

DESCRIPTION

FIG. 1 is a top elevational view of an occlusal dental mirror, polished to a mirror finish on both top and bottom surfaces, showing our new design;

FIG. 2 is a side elevational view thereof;

FIG. 3 is a bottom elevational view thereof;

FIG. 4 is a back view thereof;

FIG. 5 is a front view thereof; and,

FIG. 6 is a perspective view thereof.
